OSCAR G. KLUGEL, OF INDIANAPOLIS, INDIANA, ASSIGNOR OF ONE-HALF TO ELMER E. CRANE, OF INDIANAPOLIS, INDIANA.

CIGAR-LIGHTER.

1,076,583.

Specification of Letters Patent.

Patented Oct. 21, 1913.

Application filed March 27, 1913. Serial No. 757,102.

To all whom it may concern:

Be it known that I, OSCAR G. KLUGEL, a citizen of the United States, and a resident of Indianapolis, in the county of Marion and State of Indiana, have invented a new and Improved Cigar-Lighter, of which the following is a full, clear, and exact description.

My invention has special reference to cigar 10 lighters, although it is very obvious that the device may be employed for lighting a pipe or cigarette.

In carrying out my invention, it is my purpose to provide a lighting appliance of 15 the above character employing gas for producing a flame, and which may be suspended in convenient position for use, the device being so constructed as to be positioned for convenient use by persons of different 20 heights and which will, when at a state of rest, burn with a small or pilot flame, but which when operated through the instrumentality of a swinging lever under spring tension, will cause the flow of an increased 25 volume of gas to produce a larger flame or blast which will require but a minute time to light a cigar or the like.

Another object of this invention resides in the provision of a novel arrangement of 20 operating parts associated with a pivoted burner carried by a supply conduit for quickly and easily shifting the burner to a lighting position, as when in use, but in which the parts will automatically return 35 to an inoperative position and be normally at a state of rest when burning with a small flame, thus proving an economical gas user.

A still further and important object of 40 the invention is to provide novel regulating means for controlling the amount of volume of gas which shall be supplied to the burner, both when in a normal position and when operated for lighting purposes.

With the above and other objects in view, 45 the invention resides more particularly in the peculiar combinations and arrangements of parts which will be illustrated as a preferred embodiment in the accompanying drawings and described in the specification.

Reference is to be had to the accompanying drawings forming a part of this specification, in which similar characters of reference indicate corresponding parts in all the views, and in which—

55 Figure 1 is a perspective view of a gas cigar and pipe lighter illustrating the pre-

ferred embodiment of the invention; Fig. 2 is a side elevation of the device in a lighting position, as when in use, in contra-distinction to the normal or inoperative position of the device shown in Fig. 1; Fig. 3 is an enlarged sectional view through the supply valve for the burner to illustrate the relative positions of the ducts through the valve and to the burner; Fig. 4 is an 60 enlarged cross sectional view taken through the regulator carried by the supply conduit, the section on the supply valve being taken transversely through the feed duct thereof; and Fig. 5 is an enlarged sectional view 65 showing the manner of pivoting the operating lever and illustrating the spring means provided to hold the lever normally in a vertical or inoperative position.

In the illustrated embodiment of the invention, my improved cigar and pipe lighter is shown as being suspended by a supply pipe, preferably in the form of a flexible tube 10 to which is coupled in any preferred manner a rigid supply conduit 11, it being 70 understood that the tube is connected with a supply pipe for gas having any well known source of generation. The lower extremity of the conduit 11, which latter is preferably vertically positioned under normal circumstances, carries an enlargement 75 12 preferably threaded thereon as shown, and such enlargement is provided with a depending stem 13 terminating at its lower end in a cylindrical barrel 14 having a counterbored end 15 terminating in a central reduced and threaded portion 16.

A cap 17 is fitted over the barrel 14, being provided with a co-acting counterbored face producing a sleeve extension 18 for this purpose, and said parts are connected for independent rotation through the medium of a pivot screw 19 having a reduced portion engaged with the threaded part 16. A lever connects with the cap 17 and embodies an 95 upwardly extending arm 20 and a depending stem removably carrying a handle 21 producing the other arm of the lever, it being observed that the handle normally depends from the connection. In order to 100 hold the lever normally in a vertical position spring means are provided, the same consisting of a coiled spring 22 engaged in the counterbore 15 and receiving the pivot screw 19 therethrough, the extremities of 105 the spring being bent at right angles in opposite directions and one extremity engag-

ing a recess 23 in the end wall of the counterbore 15 while the other extremity may be adjusted in either of a series of recesses 24 in the end wall of the cap counterbore, so 5 as to adjust the tension of the spring and the normal tendency of the latter to hold the lever in a vertical position.

The conduit 11 communicates with a 3-way passage in the enlargement 12, the 10 outer portion being somewhat reduced and threaded as shown at 25, in which portion a sleeve nut 26 is threaded and said sleeve nut has a jam nut 27 exteriorly threaded thereon. The sleeve nut is interiorly threaded, 15 the pitch of these threads being considerable less than the pitch of the exterior threads, having engaged therein a relatively elongated stem 28. A forwardly extending pipe section 29 leads from the enlargement 20 12 and interiorly communicates therewith, besides serving to receive the stem 28 therethrough, and said stem is provided with a right-angular lug 30 near its threaded end which engages a longitudinal recess 31 in 25 the inner wall of said pipe so as to hold the stem against rotation but to permit it to be minutely adjusted longitudinally by rotating the sleeve nut 26. This action is due to the differences in the pitch of the threads 30 as above mentioned, and in practice the threads of the stem and the enlarged threads of the sleeve nut are cut 40 gage and the exterior threads of the sleeve nut 36 gage so that the stem will move about one-tenth of 35 an inch in thirty-six full turns of the sleeve nut, when the jam nut 37 may be operated to anchor the parts against movement by abutting the enlargement 12.

The free end of the pipe section 29 carries a valve casing 32, the bore of which is tapered, as shown in Fig. 3 of the drawings, and the bore of the section 29 at its outer portion communicating with the interior of the valve casing is reduced in diameter, as 45 shown at 33, such portion snugly receiving the adjacent portion of the stem 28 for movement therein as the stem is adjusted. The stem at this point is provided with a transverse aperture 34, and communicating 50 with this aperture is a central longitudinal passage 35 which communicates with the outer end of the stem. Fitted to oscillate in the casing 32 is a turn valve 36, the same having a longitudinal passage 37 extending 55 a portion of its length and terminating at its inner end in a radial passage 38 extending to the periphery of the valve and communicating with the passage 35 by means of a peripheral recess 39 extending substantially one-quarter way around the valve. 60 This recess 39 is uniform in size toward its end which communicates with the passage 33, this being the position of the valve when the parts are located as in Fig. 4 of the 65 drawings, so that the amount or volume of

gas which is supplied through the valve must pass the narrow passage point 40, thus supplying a minimum amount of gas to the burner.

One end of the valve 36 is provided with a 70 reduced flattened portion 41 which projects beyond the casing end and has a washer 42 fitted thereon, and the same end of the valve is provided with a threaded bore engaged by a binding screw 43 which serves to hold the valve in position and to regulate its freedom of motion, while the washer 42 produces a bearing surface and prevents displacement of the valve. The extended end of the valve is provided with a vertical 75 burner pipe 44 which is tapered toward its upper end, and which is provided with a tapered bore 45 producing a very restricted burner nozzle. The lower end of the bore communicates with the passage 37 through 80 the opening 46 communicating with the bottom of the valve, and a needle valve 47 operates in this opening to coöperate with a seat produced by the end wall thereof to open or close the passageway to regulate 85 the supply of gas, especially when the valve 36 is completely open and the radial passage 38 communicates with the passage 35 of the stem 28.

The nozzle of the burner pipe 44 is exteriorly threaded for the removable attachment of a globe 48 through the instrumentality of a sleeve portion 49, while said globe is held from rotation by means of a set screw 50 engaged through the sleeve and 100 with the exterior surface of the burner pipe. It will be observed that the globe almost completely incloses the nozzle of the burner, the top portion only being open and a hood 51 being positioned thereover to prevent the 105 light from being extinguished. This hood is supported by an arm 52 having a sleeve portion 53 radially adjustable on the conduit 11 so as to dispose the hood directly over the burner, and the set screw 54 engaging 110 through the sleeve and with the conduit serves to hold the arm in the desired adjusted position.

In Fig. 1 of the drawings it will be observed that the conduit 11 is vertically arranged and mounted for pivotal movement as described, and that the burner and globe carried thereby are also vertically disposed, the parts in this position being as illustrated in Fig. 4, so that a minimum amount of gas 115 will be supplied to the nozzle for producing a small pilot flame. However, when it is desired to move the parts to the position shown in Fig. 2 of the drawings for lighting a cigar, pipe or cigarette as the case may be, the upper arm of the lever is pivotally connected by a link 55 to an arm 56 extending rearwardly from the burner part, so that by swinging the grasping or handle part of the lever rearwardly in the manner illustrated 120 125 130

in Fig. 2, the arm 20 is caused to swing forwardly, thus moving the burner to a forward position. In thus oscillating the parts, the valve 36 will be turned until the radial passage 38 communicates with the passage 35 and the flow of gas increased to produce a large flame or blast which will project or exude from the nozzle through the open end of the globe and the lighting operation will 10 be completed in an instant.

As above mentioned, the spring 22 normally serves to hold the operating lever in a vertical position, but in order to so limit the movement of the lever the arm 56 is 15 provided with a rearwardly extending upper projection 57 which engages the top portion of the link 55 and forms a stop. To limit the movement of the parts to an operative position, the arm is provided with a depend- 20 ing projection 58 which engages the bottom face of the link and also forms a stop, so that the burner is limited in its movement to a horizontal position. It is, however, apparent that since the burner swings in an 25 arc of 45° from a vertical to a horizontal position, a relatively wide range of movement is provided so that the burner can be adjusted to persons of different heights.

Having thus described my invention, what 30 I claim as new and desire to secure by Letters Patent is:—

1. A gas cigar and pipe lighter comprising the combination with a vertical supply pipe for gas; of a barrel at the lower end 35 thereof, a lever pivoted to the barrel and extending above and below the same, spring means carried by the barrel and acting on the lever to normally hold the lever in an upright position, a supply pipe leading out- 40 wardly from the first-mentioned supply pipe and formed at its outer end with a valve casing, a valve operating therein and having a burner pipe receiving a supply therefrom, and a connection between the 45 burner pipe and the lever for operating the valve.

2. A gas cigar and pipe lighter comprising the combination with an upright supply pipe for gas; of a barrel at the lower end 50 thereof, a lever pivoted to the barrel and extending above and below the same, spring means carried by the barrel and acting on the lever to normally hold the lever in an inoperative position, a supply pipe leading 55 outwardly from the first-mentioned supply pipe and formed at its outer end with a valve casing, a valve operating therein and having a burner pipe receiving a supply therefrom, said valve having a supply duct 60 leading to the burner and adapted to supply a minimum amount of gas thereto when the parts are in their initial position, and a link connection between one arm of the lever and the burner, whereby when the lever is moved

on its pivot against the action of the spring 65 means afore-mentioned said valve will be oscillated with the burner to supply an increased amount of gas to the latter for lighting purposes.

3. A gas cigar and pipe lighter comprising 70 the combination with a suspended supply pipe for gas; of a barrel at the lower end thereof, a lever pivoted to the barrel and extending above and below the same, spring means carried by the barrel and acting 75 on the lever to normally hold the lever in an upright position, a supply pipe leading outwardly from the first-mentioned supply pipe and formed at its outer end with a valve casing, a valve operating there- 80 in and having a burner pipe receiving a supply therefrom, a connection between the burner pipe and the lever for operating the valve, a globe surrounding the nozzle of the burner and having an opening for the pas- 85 sage of the blast therethrough when the burner is in lighting position, and means to limit the movement of the valve in either direction.

4. A gas cigar and pipe lighter comprising 90 the combination with a suitably supported supply pipe for gas; of a barrel at the lower end thereof, a lever pivoted to the barrel and extending above and below the same, spring means carried by the barrel 95 and acting on the lever to normally hold the lever in an upright position, a supply pipe leading outwardly from the first-mentioned supply pipe and formed at its outer end with a valve casing, a valve operating there- 100 in and having a burner pipe receiving a supply therefrom, a connection between the burner pipe and the lever for operating the valve, a globe surrounding the nozzle of the burner and having an opening for the pas- 105 sage of the blast therethrough when the burner is in lighting position, and a hood carried by the gas supply pipe first mentioned for disposal over the burner globe.

5. A gas lighter of the class described 110 comprising a supply pipe adapted for connection with a suitable source of gas supply, a valve having communication with said supply pipe and having a longitudinal passage and a radial passage com- 115 municating therewith, said radial passage terminating in a recess normally communicating with the pipe at its free end, a vertically disposed burner nozzle communicating with the longitudinal passage of the valve 120 and receiving a minimum supply of gas when the valve is in the position named, means for regulating the flow of gas through the pipe and passage, and means for causing the nozzle to assume a horizontal position to supply a maximum amount 125 of gas thereto.

6. A gas lighter of the class described

comprising a supply pipe adapted for connection with a suitable source of gas supply, a barrel at the lower end thereof, a lever pivoted to the barrel and extending above and below the same, means for holding the lever in an upright position, a supply pipe leading outwardly from the first-named pipe and formed with a valve casing, a valve in the casing having a nozzle and having communication with said supply pipe, said valve also having a longitudinal passage and a radial passage communicating therewith, said radial passage terminating in a peripheral recess normally communicating with the longitudinal passage of the valve and receiving a minimum supply of gas when the valve is in the position named, means for shifting the valve from the lever to aline the radial passage for communication with the supply pipe, whereby an increased amount of gas will be supplied to the nozzle for producing a blast, and means for controlling the supply of gas from the pipe through the recess and radial passage of the valve.

7. A lighter of the class described embodying a vertical supply pipe, an enlargement carried by the lower end of the pipe and having a depending stem, said enlargement having a feed passage communicating with the pipe, a pipe section extending forwardly from one passage of the enlargement, a vertically extending pivoted burner having communication with said pipe section to receive a supply of gas therethrough, link connections between the stem and burner, and means carried by the stem for swinging the burner in an arc of 90° or less for raising and lowering the same.

8. A lighter of the class described embodying a vertical supply pipe, an enlargement carried by the lower end of the pipe and having a depending stem, said enlargement having a feed passage communicating with the pipe, a pipe section extending forwardly from one passage of the enlargement, a burner having communication with said pipe section to receive a supply of gas therethrough, means carried by the stem for raising and lowering the burner, said burner being adapted to burn with a pilot flame when in raised position and at a large flame when shifted from said position, and stop members carried by the

burner to limit its movements in either direction.

9. A lighter of the class described embodying a vertical supply pipe, an enlargement carried by the lower end of the pipe and having a depending stem, said enlargement having a 3-way passage communicating with the pipe, a pipe section extending forwardly from one passage of the enlargement, a burner having communication with said pipe section to receive a supply of gas therethrough, a sleeve nut threaded in the opposite passage of the enlargement, a valve stem having threaded engagement with the interior portion of the sleeve nut and having passages at its opposite end leading through the pipe section, a valve establishing communication between the said passages and the burner, and means to hold the valve stem against rotation whereby it will be longitudinally shifted toward and away from the valve upon rotation of the sleeve nut, said sleeve nut having threads of different pitch.

10. A lighter of the class described embodying a vertical supply pipe, an enlargement carried by the lower end of the pipe and having a depending stem, said enlargement having a 3-way passage communicating with the pipe, a pipe section extending forwardly from one passage of the enlargement, a burner having communication with said pipe section to receive a supply of gas therethrough, a sleeve nut threaded in the opposite passage of the enlargement, a valve stem having threaded engagement with the threaded portion of the sleeve nut and having passages at its opposite end leading through the pipe section, a valve establishing communication between said passages and the burner, means to hold the valve stem against rotation whereby it will be longitudinally shifted with relation to the valve upon rotation of the sleeve nut, and means to lock the sleeve nut against rotation.

In testimony whereof I have signed my name to this specification in the presence of two subscribing witnesses.

OSCAR G. KLUGEL.
